UNITED STATES PATENT OFFICE.

CHARLES T. WITTSTEIN, OF NEWARK, NEW JERSEY.

JEWELRY TAG.

Application filed October 15, 1923. Serial No. 668,778.

To all whom it may concern:

Be it known that I, CHARLES T. WITTSTEIN, a citizen of the United States, and a resident of Newark, in the county of Essex and State of New Jersey, have invented a new and Improved Jewelry Tag, of which the following is a full, clear, and exact description.

This invention relates to an improved jeweller's tag and has for an object to provide a construction which may be quickly and easily applied and which presents a pleasing appearance when in use.

Another object of the invention is to provide a jeweller's tag in which the tag is made from celluloid or other material capable of being washed without injury, the construction being such that the tag may be readily applied by the fingers.

20 In the accompanying drawing—

Figure 1 is a side view of a ring with the tag embodying the invention shown applied thereto.

Figure 2 is a plan view of the tag before it is applied.

Figure 3 is a view similar to Figure 2 but showing the opposite side thereof.

Figure 4 is a sectional view through Figure 2, approximately on line 4—4, the same 30 being on an enlarged scale.

Figure 5 is a sectional view on an enlarged scale through Figure 1, approximately on line 5—5.

Figure 6 is a transverse sectional view 35 through Figure 5, on line 6—6.

In providing tags for jewelry, a comparatively small structure is desirable and one that may be readily applied and also readily removed. Heretofore, several different 40 forms of tags have been used, including a paper tag having a neck portion threaded through certain parts of the jewelry. This tag is satisfactory up to certain limits but will not answer all requirements as the tag 45 becomes soiled and even torn when the jewelry is cleaned. After the cleaning of a ring or other piece of jewelry, it is always necessary to apply a new tag which adds a slight expense and which occupies 50 an appreciable amount of time. According to the present invention, a tag has been provided which will have all of the advantages of the old paper tag and in addition, will have advantages not present in the paper

tag, as for instance, the advantage of withstanding the action of water or other cleaning material.

As indicated particularly in Figures 2 and 3, the tag embodying the invention is provided with a neck section 1 merging into end sections 2 and 3. This tag is formed preferably from celluloid and in the forming the end section 3 has its edges bent over for presenting a retaining flange structure 4. The end section 3 is also provided with an annular recess or groove 5 on the rear face whereby a central bulged portion 6 is presented to the fingers when the tag is to be applied. The section 2 is merely a disk-shaped end or enlargement of neck 1 and is adapted to be snapped into the position shown in Figures 5 and 6 when bent over as illustrated in Figure 1.

In applying the tag, the section 2 is threaded through the ring or other piece of jewelry and then bent until the section 2 is superimposed on the section 3. These two sections are then grasped between the thumb and finger and pressed together until the section 2 snaps beneath the flange 4. It will be noted that the central bulged portion 6 projects outwardly so as to be readily pressed by the thumb and finger when the section 2 is being forced beneath the flange 4. It will be noted that the flange 4 is cut away at one point for permitting part of the neck 1 to permit the section 2 to properly engage section 3. After the parts have been applied as shown in Figure 1, they are left in that position continually until the article 90 of jewelry has been sold, when the neck 1 is broken and the tag removed.

As the tag is made from celluloid or similar material, it may be cleaned at the same time as the article of jewelry without any injury thereto or if it is not desirable to clean the tag, the article of jewelry may be cleaned without breaking the tag. In forming the tag it has been found desirable to form the same of celluloid substantially the shape shown in the drawing but it will be evident that if desired, the tag might be formed from metal or some other waterproof material. It is also evident that the flange 4 could be a complete flange as shown in Figure 3 of the drawing or could consist of suitable sections of flange designed to interlock with the enlarged end 2.

What I claim is:—

1. A tag for jewelry formed from a single piece of celluloid and constructed with substantially flat enlarged ends, one of which is formed with a clamping flange adapted to interlock with the edge of the other end when the ends are forced together flatwise for locking the tag to an article of jewelry. 25
2. A tag for jewelry, comprising a structure of waterproof material formed with a neck adapted to be looped through an article when the tag is in use, and enlarged ends of substantially equal size formed integral with the said neck, one of said ends being provided with an encircling locking flange co-acting with the other enlarged end for locking the parts in a folded position. 30
3. A jeweller's tag, comprising a structure of waterproof material having a rounded end section, and a neck projecting from said end section, and a second rounded end section provided with a flange adapted to receive the first mentioned end section when the neck is folded whereby said sections are locked together. 35
4. A jeweller's tag, comprising a structure of waterproof material having a pair of enlarged ends and a connecting neck all formed of one piece, one of said ends having the edge turned over forming a flange, said flange being adapted to act as a lock for the opposite end when said opposite end is folded over and pressed against the end having the turned over flange. 40
5. A jewelry tag comprising a waterproof body having a pair of enlarged ends one of said ends having its edge turned over for forming a flange on one face, said end being depressed near said edge for presenting an annular groove while the central portion presents a projecting rounded section said flange being adapted to be snapped over the edge of the other enlarged end when said ends are forced together flatwise. 45

CHARLES T. WITTSTEIN.
